(57) **CLAIM**

The ornamental design for a milling machine, as shown and described.

DESCRIPTION

FIG. 1 is a perspective view of a milling machine, showing our new design.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top view thereof; and,

FIG. 7 is a bottom view thereof.

The broken lines shown in the figures are included for the purpose of illustrating portions of the milling machine and form no part of the claimed design.

1 Claim, 7 Drawing Sheets
